FLORINDA GARDNER, OF TAMPA, FLORIDA, ASSIGNOR, BY MESNE ASSIGNMENTS, OF
ONE-HALF TO BEULAH N. BENTLEY, OF TAMPA, FLORIDA

WOMAN'S GARMENT

Application filed December 17, 1927. Serial No. 240,825.

This invention relates to a garment of the slip-on type for women and has for its object to provide, in a manner as hereinafter set forth, a slip so constructed and arranged 5 to protect an outer garment from soiling or becoming damaged during certain periods of illness.

A further object of the invention is to provide, in a manner as hereinafter set forth, 10 a slip so constructed and arranged to prevent the creasing and unsightly appearance of outer garments caused by perspiration of the body while the wearer is seated and thus helps the wearer in appearance of such outer garments.

A further object of the invention is to provide, in a manner as hereinafter set forth, a slip for the purpose referred to and which overcomes the use of binding rubber or elastic 20 of any kind around the legs or body of the wearer.

Further objects of the invention are to provide, in a manner as hereinafter set forth, an undergarment of the slip-on type which is 25 simple in its construction and arrangement strong, durable, light in weight, thoroughly efficient in its use, not uncomfortable when worn, and comparatively inexpensive to manufacture.

30 With the foregoing and other objects in view the invention consists of the novel construction, combination and arrangement of parts as hereinafter more specifically described, and illustrated in the accompanying 35 drawings, wherein is shown an embodiment of the invention, but it is to be understood that changes, variations and modifications can be resorted to which fall within the scope of the claim hereunto appended.

40 In the drawings wherein like reference characters denote corresponding parts throughout the several views:

Figure 1 is a rear elevation of a slip-on garment in accordance with this invention and illustrating the protecting element in dotted lines.

45 Figure 2 is a vertical sectional view of the garment showing the position of the protecting element at the inner face of the back of the garment.

Figure 3 is a perspective view of the protecting element.

Referring to the drawings in detail, 1 generally indicates an under garment of the one-piece slip-on type having a pair of sides, a 55 front and a back and formed of a closed waist portion or part 2, a closed skirt portion or part 3 and a pair of spaced suspension straps 4, 5 at the top of the waist portion or part 2.

Secured at their inner ends to the inner 60 face of the back and in proximity to the sides of the garment, at the waistline of the latter, is a pair of spaced, flexible tie members 6, 7.

Positioned against the inner face of the back of the skirt portion or part 3 and extending from the waistline of the garment to a point an appropriate distance below the transverse median of the skirt portion or part 3 is a protecting element referred to generally 65 at 8.

Carried by the protecting element 8 is a 70 flexible attaching member 14 having its intermediate portion secured to element 8. The member 14 is of a length to have the end terminal portions 9, 10 thereof project laterally 75 in opposite directions from the sides of element 8. The end terminal portions 9, 10 contact with the tie members 6, 7 for attaching the element 8 in position relative to the inner face of the back of the closed skirt portion or part 3.

The protecting element 8 is formed of a thin, flexible sheet like body portion 11 which is impervious and preferably constructed of a thin sheet of rubber of the desired length. 80 The body portion 11 gradually decreases in width from its upper end to the lower end. The body portion is folded upon itself, at its top, as at 12 and with the fold secured in position by a row of stitching 13 to provide 85 a hem for reinforcing the upper end of the body portion. The body portion 11 is formed with rounded lower corners 16, 17 and has a free lower end.

The attaching member 14 is formed from a 90 single length of flexible material of the desired width, bent upon itself at its transverse median and has the intermediate portion thereof overlapping the hem at the top of the element 8. The folds of the member 14 are 95 100

secured together and to the part of body portion 11 by a row of stitching 14 which extends from end to end of the attaching member.

When the end terminal portions 9, 10 of 5 the attaching member 14 are connected with the tie members 6, 7 the element 8 is suspendingly secured from the waistline of the body of the garment within the latter at the back thereof and opposes the inner face of the back 10 of the closed skirt part.

The slip when worn is not uncomfortable, as the element 8 allows a free circulation of air between it and the wearer, yet at the same time the element 8 is always in place and 15 serves the purpose for which it is intended. Further setting up the slip with a protecting element in the manner as referred to overcome the necessity of using binding rubber or elastic of any kind around the legs or 20 body of the wearer. The slip when worn prevents the soiling of outer garments, of women at all times and furnishes the advantages of sanitary aprons, rubber pants and other devices at a materially less cost and with greater 25 comfort. As the element 8 is detachably secured in position, it can be easily taken out and enables the wearer to launder the slip, as well clean the element 8. Furthermore the element 8 can be wiped off at any time with 30 a damp cloth thus doing away with the ruining of garments commonly ruined by washing, manipulation, machinery or hot irons. Therefore, it is thought the many advantages 35 of a garment, in accordance with this invention can be readily understood, and although the preferred embodiment of the invention is as illustrated and described, yet it is to be understood that changes in the details of construction can be had which fall within the 40 scope of the invention as claimed.

What I claim is:

A garment for the purpose set forth comprising the combination of a one-piece slip-on body having a pair of sides, a front and a 45 back and consisting of a closed waist part and a closed skirt part, a pair of spaced flexible tie members having their inner ends secured to the inner face of said back at the waist line of said body, a thin, flexible, impervious protecting element of sheet like 50 form arranged against the inner face of the back of the closed skirt part, having the upper end thereof positioned at the waistline of said body and of a length to extend from 55 the waistline to position its lower end at a point below the transverse median of said closed skirt part, said element gradually decreasing in width from its upper to its lower end, and a flexible attaching member having 60 its intermediate portion secured to said upper end of said element and of a length to have its end terminal portions project laterally in opposite directions from the sides of said element, said end terminal portions coacting 65 with said tie members for suspendingly se-

curing said element from the waistline of said body to oppose the inner face of the back of said closed skirt part whereby a free circulation of air between said element and the wearer of the garment is had when the wearer is 70 standing and protection is had for the back of the closed skirt part when the wearer is seated.

In testimony whereof, I affix my signature hereto.

FLORINDA GARDNER.
